ATTORNEY.

UNITED STATES PATENT OFFICE.

WILLIAM B. HUGHES, OF CLEVELAND, OHIO.

GAS-PRODUCER.

No. 894,146.

Specification of Letters Patent.

Patented July 21, 1908.

Application filed August 7, 1907. Serial No. 387,417.

To all whom it may concern:

Be it known that I, WILLIAM B. HUGHES, a citizen of the United States, residing at Cleveland, in the county of Cuyahoga and State of Ohio, have invented certain Improvements in Gas-Producers, of which the following is a specification.

This invention is a gas producer having improved means for feeding and distributing 10 the fuel.

In its preferred form it comprises a fuel supply conduit which delivers to a hopper eccentrically placed on a revolving producer top, with reciprocating bars for controlling 15 the flow through the supply conduit and a valve for controlling the delivery from the hopper, the bars and valve being connected so that they act in alternation to stop the flow of fuel through the respective passages controlled by them.

The characteristic features and advantages 20 of the invention will more fully appear by reference to the following description and the accompanying drawings in illustration 25 thereof.

In the drawings, Figure 1 is a broken plan view of a producer made in accordance with the invention and Fig. 2 is a vertical sectional view thereof.

As shown in the drawings, the producer body 1 has thereon the circular channel 2. The producer top 3 has the cylindrical apron 4 disposed in the channel, the top being carried by the wheels 5 which are journaled 30 thereon and run on the circular track 2' provided by the outer wall of the channel. The hopper 6 is placed eccentrically on the producer top and delivers through the passage or port 7, being supplied through the conduit or passage 8 centrally disposed with relation to the producer and revoluble about the supply pipe 8'. The hopper may also be supplied through the passage or port 9 having the cover 10. The passage 7 is controlled 40 by the vertically reciprocating cone valve 11 which is connected by a link 12 with an arm 13 fixed to the shaft 14, the latter being journaled in the bearing 15 carried by the hopper. The passage 8 is controlled by the horizontally 45 reciprocating bars 16 which are fixed to a cross piece 17 connected by a link 18 with an arm 19, the latter being fixed on the shaft 14 with relation to the arm 13 so that when the valve 11 is raised to close the passage 7

the bars 16 are withdrawn to open the passage 8 and vice versa.

An arm 20 is fixed to the shaft 14 in such relation to the arms 13 and 19 that a weight 21 on the arm 20 will hold the valve and bars in position to either open or close their respective passages, depending upon the side of the shaft 14 occupied by the weighted arm.

It will now be understood that the fuel supply in the passage 8, for charging the hopper 6, will be penetrated and held by the bars 16 simultaneously with the lowering of the valve 11 to discharge the hopper; and when the valve is raised to close the hopper the bars are withdrawn to permit the supply to recharge the hopper. Fuel from the centrally placed stationary supply pipe 8' may thus and by means of the revoluble top be distributed at will within the body, with slight loss of gas by reason of the tight construction and the obstruction of the fuel supply.

Having described my invention, I claim:

1. In a gas producer, a conduit, a horizontally movable bar for controlling the passage 80 of matter through said conduit, a vertically movable cone valve for controlling the passage of matter through said conduit, and mechanism connecting said bar and valve whereby they are operated together.

2. In a gas producer, a conduit comprising a hopper, one or more reciprocating bars for controlling the flow of matter to said hopper, a vertically reciprocating valve for controlling the discharge from said hopper, and 90 mechanism connecting said bar or bars and valve for simultaneously inserting said bar or bars to stop the flow to said hopper and withdrawing said valve to permit flow from said hopper.

3. A gas producer having a revoluble top, a hopper having an inlet centrally disposed and an outlet eccentrically disposed with relation to said top, a device reciprocating transversely to the direction of flow through 100 said hopper, and, for controlling the passage of matter through said inlet, a vertically reciprocating device for controlling the passage of matter through said outlet, and means connecting said devices to effect their correlative operation.

4. A gas producer having a revoluble hopper with a centrally disposed inlet and an ec-

centrically disposed outlet, horizontally reciprocating bars for controlling the passage of fuel through said inlet, a vertically reciprocating valve for controlling said outlet, and 5 mechanism whereby said bars and valve are operated together.

In testimony whereof I have hereunto set

my name this sixth day of August, A. D., 1907, in the presence of the subscribing witnesses.

WILLIAM B. HUGHES.
